UNITED STATES PATENT OFFICE.

JACOB WOOLNER, OF PEORIA, ILLINOIS.

APPARATUS FOR COOLING MASH.

SPECIFICATION forming part of Letters Patent No. 292,885, dated February 5, 1884.

Application filed November 23, 1883. (No model.)

To all whom it may concern:

Be it known that I, JACOB WOOLNER, of Peoria, in the county of Peoria, in the State of Illinois, have invented an Improved Apparatus for Cooling Mash; and I do hereby declare that the following is a full, clear, and exact description thereof, reference being had to the annexed drawings, making a part of this specification, in which like letters of reference refer to like parts, and in which—

Figure 1 represents a plan view of the apparatus; Fig. 2, a vertical section.

The object of this invention is the construction of apparatus for cooling mash preparatory to its fermentation in the manufacture of spirits that shall be in a high degree economical in its use of water, and that shall also employ the minimum number of mash-pumps. To effect this purpose I have devised the following construction:

F F' are two tubs—preferably oval in plan—in each of which is a coil of copper pipe. The head of the coil C² in the tub F is connected with the pump B by a suitable pipe, C', while its tail is joined by the pipe C⁴ to the head of the coil C⁵. The tail of this latter coil C⁵ communicates with the fermenting-tubs, or to a spout leading thereto. The suction-pipe C extending from the pump B to the mash-receiver A enables said pump to force the mash from said receiver through both the coils C² C⁵ to the fermenting tub or tubs T. The tubs F F' being filled with water, cool as can be obtained, the coils C² C⁵, and therefore the mash flowing through them, are brought to the desired low temperature. The means by which these tubs F F' are kept constantly filled with cool water—and no water is lost until it has taken as much heat as possible—is as follows:

E is a pipe, terminating at the bottom of the tub F' in a T, by which a constant stream of cold water is admitted and directed horizontally toward the coils C⁵. From the upper edge of the tub F' is an overflow-pipe, E², which runs to the bottom of the tub F, and is there supplied with a T-pipe, E³, similar to that of the pipe E, and for the purpose of directing against the coils C² the cooler water overflowing from the tub F'. The tub F is given an overflow-pipe, O, by which the heated surface-water therefrom may be di-

rected to the waste-drain, or wherever else desired.

The temperature of the mash in the receiver A is from 150° to 152°; but the temperature which it must have in the fermenting-tubs is about 65°. The water about the coils C² C⁵ is therefore obliged to extract about 85° of heat from all the mash passing through them. Were this entire amount of heat to be dissipated into the water of the tub F, there would have to be a very rapid inflow of cold water and exit of the same when only slightly warmed; but by having the partially-warmed water overflow from the tub F and surround the coil C² in the tub F, the hot mash passing through said coil is cooled down to approximately the temperature of this lukewarm water in the tub F before it gets to the coil C⁵, and is cooled therein to the desired degree. It is therefore evident that this construction effects a great saving in the amount of water used, not only for the reason just described, but for the increased exposed surface which is given the water by being contained in two open tubs instead of one alone. The increased exposed surface permits increased evaporation of the water, and thereby keeps it somewhat cooler. By having the hottest mash cooled in the warmed water of the tub F, the joints, elbows, and pipes themselves of the coils C² C⁵ are saved from the strain which would ensue from the unequal expansion consequent upon their containing an extremely hot liquid, but being immersed in cold water.

Although I have described but two tubs, F F', I design using in the same way a series of several, so that when the water is permitted at last to escape from the tub containing the first coil, C², the temperature of said water may not be but a degree or two cooler than the mash entering the coil.

Since the coils C² C⁵ are the continuation of the same pipe, a single pump, B, serves to force the mash through them both, when if they were disconnected two pumps would be necessary. The decreased amount of cold water supplied to the tubs F F' enables me to use a comparatively small pump to supply the same.

What I claim as my invention, and for which I desire Letters Patent, is—

1. In a mash-cooling apparatus, two or more

tubs, only one of which is adapted to receive fresh supplies of cold water, each of the others being filled from the overflow of the tub before it, in combination with a coil of pipe in each tub, and connections whereby a continuous stream of mash may be pumped through them all, substantially as shown and described.

2. The tub F', having water-supply pipe E and overflow E', terminating at the bottom of the tub F, in combination with said tub F and the coils C² C⁵, continuous from one to the other, and having suitable supply-pump, substantially as and for the purpose specified.

3. The pump B, having suction-pipe C,

coils C² C⁵, having connecting-pipes C' C⁵, and exit-pipe C', in combination with the tubs F F', supply-pipe E, having a T-shaped discharge end, E', at the bottom of the said tub F', overflow-pipe E', having a T discharge end, E', and the overflow-pipe O, substantially as and for the purpose set forth.

In testimony that I claim the foregoing invention I have hereunto set my hand this 17th day of November, 1883.

JACOB WOOLNER.
